PORTABLE RECEPTACLE FOR PHONOGRAPH RECORDS

Herbert S. Chase, Woodmere, N.Y., assignor to Bernard Cahn Co., Inc., New York, N.Y.

Application May 25, 1959, Serial No. 56,046

Term of patent 14 years

(Cl. D87—3)

Figure 1 is a front elevational view of a portable receptacle for phonograph records, showing my new design in closed position.

I claim:

The ornamental design for a portable receptacle for phonograph records, substantially as shown.
